FRANK EDWARD GOECKLER, OF PHILADELPHIA, PENNSYLVANIA, ASSIGNOR OF ONE-FOURTH TO GEORGE C. KLAUDEER AND ONE-FOURTH TO JOHN COX, BOTH OF PHILADELPHIA, PENNSYLVANIA.

ELECTRICAL TIME-RECORDING SYSTEM.

Application filed December 29, 1926. Serial No. 157,641.

My invention relates to a new and useful electrical time keeping or recording system, and it relates more particularly to a remote control, automatic electric system, for indicating or recording "working" time, and also for automatically checking and recording or visually to indicate the production in a shop or plant, or more particularly for automatically and continuously checking and recording machine operations throughout a shop or plant. My novel automatic electrical "time" or "production" recording system is adapted chiefly to shops or plants comprising a large number, or a series of individual machines, such as lathes, milling machines, looms or the like, each being driven by an individual electrical motor, as is now commonly the practice in machine plants, rolling mills, textile mills and the like.

The object of my invention is to eliminate all direct time keeping operations by the workmen, such as "punching" a time clock or the like, and to place the time keeping system entirely within the control of time keepers or "operators" remotely located at some central "time-keeping" or "work dispatching" office or "recording room", having control over the entire shop, plant or factory.

A further object of my invention, moreover, is to record "time", not merely by the presence of the workmen in the plant, or at their respective machines, that is, not merely by checking the workmen "in" and "out", but to record, as nearly as possible within practical limits, the actual productive time of the workmen, that is, the time that each workman actively spends at his task. The latter end is attained by my invention, by recording what may be termed "machine time" instead of the "man" time which forms the basis of most present systems employing recording time clocks. Novel means are accordingly provided by my invention, automatically to record the actual time that each machine is in operation on "productive" work; novel means being provided however, to allow, or compensate for a "normal stoppage" of the machine, such as is necessary for changing the work in the machine and for adjusting tools, and means also for compensating for any "excusable" stoppage of the machine, other than the "normal stoppage" required for changing work, as in the event of a break-

down of the machine, necessary absence of the workman from the machine, awaiting new stock or tools or a new assignment or the like.

Thus, according to my invention, a permanent record is produced of each machine in the plant or factory, at some remote central recording room; the production of such record being dependant primarily upon an actual operation of the machine. Novel means are provided however, according to my invention, for automatically continuing the recording operation of a machine, if the machine is stopped for a limited and predetermined period of time, such time being adjustable or variable at the will of the "time keeper," so as to allow for what may be termed a "normal stoppage" of the machine, as will be required ordinarily for changing a tool or the work, without any stoppage of the time recording operation.

Thus, according to my invention, moreover, the time record, in the central recording room, will be continued so long as the particular machine is in operation, and also during a certain predetermined "normal stoppage" period allowed for the particular machine, which may be varied anywhere from a fraction of a minute to three, four, or five minutes or more, depending upon the nature of the work. If however, the machine is stopped for a greater period of time, the recording operation in the recording room, for the particular machine, will automatically cease, until the machine is again set into operation.

In order that the "machine time" record thus produced, may be used as a just and fair time record of the workman assigned to the particular machine, and as a basis of his compensation or "wages", it is also necessary to record "machine time" during certain idle periods of the machine in excess of the predetermined "normal stoppage" periods during which the time record is automatically continued, as mentioned hereinbefore. Thus, according to my invention, suitable manually operable auxiliary electrical signalling circuits and devices are provided, cooperating with and superimposed upon the recording circuits and instruments hereinbefore mentioned, for enabling a workman to maintain his time record (in the "recording room"), for certain idle periods, herein designated as "excusable

stoppage" periods. In the event that a machine must be shut down for some "excusable" cause, for a period of time greater than the "normal stoppage" period, that is, for a period greater than that ordinarily required for changing the work in the machine, the machine operator or workman need merely operate a suitable auxiliary signalling circuit, by actuating a suitable switch in the circuit, located in the immediate vicinity of the machine and within easy reach of the workman. The operation by the workman, of an auxiliary signal circuit, will then have the effect of producing a visible or audible signal (preferably the former as a colored light) both in the shop foreman's office as well as in the main, central "recording room" and also of continuing the time recording operation for the particular machine, so that a workman will not lose any time.

My invention contemplates the provision of a number of such auxiliary signalling circuits for each machine, one to correspond to each of the possible causes of "excusable stoppage" such as: (1) breakdown of the machine, (2) necessary absence of the workman from his machine, (3) awaiting a new assignment, (4) awaiting new stock, (5) awaiting tools. It is understood that these causes of "excusable stoppage" may vary, depending upon the nature of the machine and manufacturing operation, the particular illustrations herein having reference to machine shops or the like. Thus, in this particular application of my invention, if the workman contemplates a stoppage of the machine for anything more than the normal change of the work or adjustment of the tools, it will be necessary for him to operate one of the several signalling circuits provided for the purpose, in order to maintain his time record in the recording room. Thus, after the workman has operated one of the signalling circuits, thereby lighting a suitably colored (or otherwise designated) light in the foreman's office, as well as in the remotely located main recording room, it will be possible for the foreman of the particular shop, immediately to be apprised of any stoppage of a machine in his charge and to minimize such "excusable stoppage" by supplying the necessary assignment, stock, or tool without delay, or remedying any breakdown of the machine in the shortest possible time.

Thus, moreover, by the series of auxiliary electrical signalling circuits and devices of my invention, coordinated with the main electrical time recording means, the exact condition of a machine and of every machine in the factory, is visually indicated at all times at the central "recording room", whereby the management can tell at a glance, whether or not any particular machine and each and every machine in the factory is running, whether or not the stoppage is due to the absence

of the workman, or whether it is due to an excusable cause, such as a breakdown, lack of proper tool or material, or the like.

A further object of my invention is to produce a permanent time record of this character, of each machine, from which the total time of a workman, either for the day, or the week, or at any particular time, may be computed mechanically by some commercial form of mechanical calculator or accumulator, such as forms of card tabulating machines, without any mental computation of any kind on the part of the time keeping clerks.

The time record, according to my invention, may be made on any suitable piece of paper, card, or the like, and may be in the form of a straight or a curved line, the linear or angular measure of which is calibrated to represent a certain measure of time. In the preferred embodiment of my invention, however, the time record is produced by means of a suitable punch or the like, which acts upon a suitable piece of paper or "time card" or the like, and produces thereon a series of suitably spaced apertures, holes, or recesses, at predetermined and fixed short intervals of time; each aperture representing therefore such predetermined length of time. From a time record of this kind, the total time may be computed directly from the record and without any mental computation, but merely by passing such record card through a suitable mechanical counter, accumulator or the like, which will aggregate, the number of punches, apertures or recesses produced upon the record sheet or "time card". A simple mechanical multiplication of the number of apertures will then give the total time, or total wages, since each particular time punch or aperture can be made to represent a predetermined and known length of time or a corresponding predetermined measure of wages earned by the particular workman.

By this novel means, practically all time keeping and wage or "pay" computing operations employed in plants heretofore, may be eliminated, and the clerical force and overhead may be correspondingly reduced.

In some types of manufacture, it is quite possible to keep a machine running, without the machine "producing" or without any productive effort on the part of the workman, that is, merely to keep the machine running idle. In machine shops this condition is usually referred to as "cutting wind".

It is one of the objects of my invention, to enable the management of a plant, through the time keeper or "operator", either to keep a check upon the machines, as to whether or not they are "cutting wind" or whether they are "producing". A further object of my invention is not only to keep a check on the idling machines, but also, if so desired, to stop the time recording operation if the idling

continues for a certain length of time. Thus, I may provide a suitable signal light which will indicate whenever the machine is running idle and if so desired, I may also stop 5 the time recording operation during the "idling interval". A choice of one of these two alternatives is possible by my invention. For the purpose of illustrating my invention, I have shown, in the accompanying 10 drawings, forms thereof which are at present preferred by me, since they will give in practice, satisfactory and reliable results, although it is to be understood that the various instrumentalities of which my invention consists can be variously arranged and organized 15 and that my invention is not limited to the precise arrangement and organization of these instrumentalities as herein shown and described.

20 In the accompanying drawings:

Figure 1 represents a diagrammatic view, partly in perspective, illustrating the general manner in which one of the machines in a plant is connected with the remotely located, 25 central recording room, as well as with the shop office or foreman's room, by my novel electrical time recording system; illustrating more particularly, the distribution and location of the recording instrument panels and 30 signal panels.

Figure 2 represents a diagram illustrating the electrical circuits forming part of my novel invention applied to but one machine, and illustrating also the mechanical elements 35 of my invention, in a diagrammatic manner.

Figure 3 represents a diagram, similar to that shown in Figure 2, illustrating a slightly modified embodiment of my invention.

Figure 4 represents a front elevation of one 40 of the series of recording and signalling instruments or "units" comprising the main instrument panel in the central recording room.

Figure 5 represents a plan view of a recording "unit", on a slightly enlarged scale, showing 45 some of the structural details of the same.

Figure 6 represents a vertical section on line 6—6 of Figure 5, illustrating the rear view of a recording "unit".

Figure 7 represents a side elevation of a 50 "unit" taken generally on line 7—7 of Figure 5.

Similar reference characters indicate like parts.

Referring to the foregoing figures of the 55 drawings, which are diagrammatic in nature to illustrate the general principles, rather than the final and minute mechanical details, 1 designates the machine; a conventional lathe or other machine tool. While a lathe 60 has been chosen for the purposes of illustration, it is to be understood that my novel electrical time recording system is applicable to any machine which is provided with individual electrical drive, such as the electrical 65 motor 2, as for instance a loom, a knitting

machine, or the like. The electrical motor 2 may be suitably mounted either directly upon the lathe, as is frequently the practice, or otherwise, and is operatively connected with the lathe through the belt 3 and the stepped 70 pulleys 4 and 5. The electrical driving motor 2 may be of any type, such as a direct or alternating current motor, and may be either single or polyphase, and may be shunt, series, or compound wound, or of the induction type 75 of motor. In the particular illustration shown, 6, 7 and 8 designate the wires of a three phase alternating current electrical supply line or an electrical power circuit which feeds directly into a suitable starter 9, 80 which may be of any desired type, depending upon the nature of the motor, and which, in the particular illustration, is represented as an auto-transformer type of starter commonly employed with induction motors, having 85 merely a starter handle 10. From the starter 9 the wires 11, 12 and 13, lead into the motor 2. This is shown diagrammatically in Figures 1, 2 and 3.

My novel time recording system depends 90 primarily upon the current which passes into the motor of the particular machine. Thus, according to my invention, the series of recording instruments in the remotely located central recording station or room are controlled by a corresponding series of primary 95 electrical record control circuits each of which is shunted across a suitable portion of the feed line leading into one of the series of electrical motors 2, which drive the various 100 machines, in such a manner, that the electrical current in, or the voltage across these primary record control circuits, will always be proportional to the current passing through the particular motor 2.

Accordingly, I may insert into one of the feed lines 11, 12 or 13, a suitable fixed or adjustable shunt 14, which may be of any desired resistance, depending upon the resistance of the particular primary record control circuit, as well as the size of the particular motor. The wires 15 and 16, forming part 110 of the primary record control circuit, are shunted across, that is, connected to the two opposed terminals of the shunt 14, whereby a 115 voltage is maintained in the primary record control circuit and across the wires 15 and 16, which will be proportional to the current passing through the particular lead 11, and hence through the motor 2. It is to be understood that the current passing through 120 any one of the wires 11, 12 and 13, is equal to that passing through any other of said several wires of the motor load circuit.

While in the illustrations shown, the shunt 125 14 is represented merely diagrammatically and is inserted openly in the wires 11, in actual practice, such shunt will either be embodied in the starter 9, or encased and concealed in any other suitable housing, which 130

will be permanently locked, so that the shunt and the primary record control circuit can not be tampered with, in any way. Similarly, in actual practice, the leads 15 and 16 must 5 also necessarily be concealed wires, which can not easily be tampered with, or which can not be tampered with, without detection.

The primary record control circuit wires 15 and 16, are conducted to the remote central office or recording room 18, and to one of the series of recording instruments or "units" 20, on the recording or instrument board or panel 17. Each and every machine in the plant or factory is similarly connected to one 15 of the units 20 upon the instrument panel 17.

The instrument or recording board or panel 17, may be positioned in any desired manner within the recording or "time keeping" room 18, at some central point in the plant, and 20 several such instrument boards 17 may be provided to correspond to the several shops or divisions of a plant, in a manner quite similar to the division of the switch boards in a 25 telephone central office. Thus, in Figure 1, I have merely illustrated one instrument board or panel 17, corresponding to one shop, positioned in an upright manner behind any suitable record desk or cabinet 19.

Thus upon the instrument panel 17, shown 30 in perspective view in Figure 1, there are mounted a series of recording "units" designated by the numeral 20, one corresponding to each individual machine, throughout the plant, shop or division of the plant, and preferably identified by suitable numerals corresponding to the particular machine. Each of the units 20, comprises first, a recording instrument, and second, a series of indicators or signals in the form of lights suitably colored or otherwise identified, to represent the various conditions of a machine.

One of the series of recording instruments or units 20, is illustrated in Figures 4, 5, 6 and 7. Thus, upon the rear of the instrument panel 17, there is mounted first, a suitable time shaft 21, (Figure 5) extending horizontally and substantially parallel to the panel 17, and extending across the entire width thereof, and actuated at one end by 45 any suitable timing mechanism 22, which may be a motor driven clock or any other chronometric driving mechanism. The shaft 21, is preferably driven at one revolution an hour, that is, at the rate of speed of the minute hand 50 of a clock. In the illustrations shown in Figures 1 and 4, each horizontal row of units 20, is actuated by a common timing shaft 21, a separate timing shaft 21 being provided for each horizontal row of units. The several 55 timing shafts 21 may be provided with separate chronometric driving mechanisms 22, or may be intergeared and driven by a single common mechanism 22. Thus in Figures 5 and 6, the shaft 21 is shown broken, to indicate 60 that merely that portion thereof is illus-

trated, which corresponds to the unit 20, illustrated in detail in these figures.

Each unit 20, includes suitable bearing brackets 23' and 23, to support a feed screw 24. A gear 25 is mounted on one end of the 70 feed screw 24 and is permanently intergeared with the timing shaft 21, by any suitable means, such as the idle gear 26, and the driving gear or pinion 27, carried by the timing shaft 21. The intermediate or idle gear 75 26 may be suitably pivoted at 28, upon an extension of the bracket 23. The ratio between the timing shaft 21 and the feed screw or shaft 24, may be any desired ratio, depending upon the rate of the longitudinal feeding motion desired. A rigid guide rod 29 is also supported between the two brackets 23' and 23, so as to act as a guide for the carriage 30, illustrated particularly in Figures 80 5, 6 and 7, which is in threaded engagement 85 with the feed screw 24, and is guided loosely upon the guide rod 29 by the suitable bearing members 31.

The carriage 30 carries a suitable pin or horizontal projection 32, which projects 90 through an elongated slot or aperture 33, in the panel 17, and beyond the panel to a slight extent, so as to engage a suitable time card 34, by projecting therethrough at a suitable point. The time card 34, is in turn 95 guided in a horizontal direction upon the outer face of the panel 17, by any suitable means, such as the horizontal guide strips 35 and 36 respectively, which overlap the horizontal edges of the time card, as shown 100 particularly, in Figures 4 and 7. By this means the time card 34 will be moved in a horizontal direction by means of the carriage 30 and the pin 32, at the same rate as the carriage 30, and hence in a predetermined 105 and fixed timed relation to the timing shaft 21.

In order to produce a permanent visible or other record upon the time card 34, any one of several means may be resorted to, one 110 of which is shown in Figures 2, 4, 5, 6 and 7. Thus in these figures means are shown for producing a linear mark upon the time card, by means of ink or otherwise, the linear measure 115 of which represents the active working time of the particular machine.

Thus, in this modification of my invention, I may provide an arm 38, suitably pivoted at 39, and having the front end thereof projecting through a suitable aperture in the 120 panel 17 and carrying an inking device 40, which may be of any suitable construction, such as the glass ink reservoir and siphon pen illustrated more particularly in Figure 7, having a suitable writing point 41, which 125 will normally bear against the front surface of the time card 34, thereby to leave an inked mark thereon, as the card is moved horizontally in front of the inking point 41.

The arm 38, and the various elements con- 130

5 neeted therewith are so proportioned as to their weight, that the front end, that is, the portion in front of the pivot 39, will be lighter than the rear portion. By this over-
5 balancing of the front part, the inking device 40 will normally be raised in an upper portion, so as to press the inking point 41 thereof, against the time card 34. To the rear end of the arm 38 there is pivotally
10 secured a solenoid core or plunger 42, by means of the pivot pin 43. The plunger 42 is of suitable wrought iron, and extends through the center of a suitable solenoid 44, adapted to lift said core 42 in an upward
15 direction, when energized, thereby to render the recording mechanism inoperative.

Thus, the inking device will normally produce a linear mark upon the time card 34, so long as the solenoid 44 is not energized.
20 Whenever an electrical current is passed through the solenoid 44, however, of sufficient magnitude, the plunger 42 is raised, and the front end of the arm 38 is lowered, whereby the inking point 41 is retracted from
25 the surface of the time card 34, and the linear record mark upon said card is thus broken or discontinued.

In order to energize the solenoid 44, whenever the machine, corresponding to the particular recording unit, is stopped and more particularly to energize said solenoid only when the particular machine has stopped for a predetermined length of time, that is the time allowed for changing work or other
30 "normal stoppage" period, I have devised novel electrical time lag and relay switches, forming part of my novel system and illustrated particularly in Figure 2, in a diagrammatic manner. The mechanical features of
35 said time lag device are shown particularly in Figures 5, 6 and 7. Accordingly, each recording unit includes a primary or under-load relay switch or contacting mechanism 45 (Figures 2 and 3) comprising a pivotally
40 mounted magnetic core 46, in the form of a relatively thin blade of sectoral shape, pivoted at an upper point 47, and carrying a movable contact 48, upon a suitable resilient spring arm 49. The pivoted magnetic core
45 46, carried by the pivot 47, is supported from the pivot brackets 50, which in turn are carried by the outer housing 51 of the relay solenoid 52. The solenoid 52 is provided with an aperture extending therethrough,
50 adapted to receive the magnetic core 46. The solenoid 52, including the housing 51 thereof, as well as the pivot brackets 50, are in turn pivotally supported, preferably upon the rear surface of the instrument panel 17, on a horizontal pivot 93, so that the solenoid as well as the pivot 47, may be deflected or angularly
55 adjusted about a horizontal axis, thereby to vary the normal position of the magnetic core 46, with respect to the solenoid 52. The stationary contact 53 may also be adjustable, as

illustrated in Figures 2 and 3. By this means, the action of the primary relay switch 45 may be advanced or retarded, that is, adjusted to any desired current flow in the primary record control circuit 15, 16 and 52. 70

As will be seen in Figures 2 and 3, the conductors 15 and 16 of the primary record control circuit are connected in series with the solenoid 52 of the primary relay contacting mechanism 45. The resistance of the 75 shunt 14 and the resistance of the primary record control circuit, including the wires 15 and 16 as well as the winding of the solenoid 52, are so proportioned, that when the motor 2 is running under a normal working load, the solenoid 52 will be energized sufficiently to raise and hence to withdraw the magnetic core 46, a sufficient extent, so as to separate the contacts 48 and 53, and thus to break the secondary record control circuit 80 of which the contacts 48 and 53 form a part.

The contacts 48 and 53 of the primary relay contacting mechanism 45, are connected in series, through suitable conductors 85 54, 55, 56 and 57 with any suitable source 90 of electrical energy, such as the battery 58 and also in series with a signal 59, and the magnetic winding 60, of an electro-magnetic time relay or time lag switch device 61, so that said time relay will be energized whenever the primary relay solenoid 52 is de-energized to release from its hold the magnetic core 46, and thus to close the contacts 48 and 53. 95

Thus, so long as the particular motor 2 is 100 in operation, and in consequence thereof, a current passes through the primary record control circuit, that is, the wires 15 and 16 thereof and the solenoid 52, the contacts 48 and 53 will be open and no current will pass 105 through the magnetic winding 60. As the motor 2 is stopped, however, and thus no current passes through the shunt 14 and hence the wires 15 and 16 of the primary record control circuit, and the solenoid 52, 110 the contacts 48 and 53 are automatically closed by gravity and the magnetic winding 60 is thus energized by the electrical current from the battery or other source of electrical energy 58. 115

As shown in Figures 2 and 3, the magnetic winding 60 is wound about the lower horizontal portion 62 of a generally horseshoe shaped magnetic core,—the two upright limbs 63 of which approach each other at an 120 upper point so as to form two opposed magnetic poles. The magnetic core 61 may be supported rigidly upon the rear of the panel 17 in any suitable manner, and in the illustrations shown, it is carried by a suitable 125 horizontal bracket, to which it is secured by the screw 64.

The magnetic core of the time relay 61 is so positioned with respect to the timing shaft 21 that the two opposed poles 63 of 130

said magnetic core will be positioned on either side of the timing shaft, as shown particularly in Figures 2, 3, 5, 6 and 7. Each of the recording units 20, also includes a 5 constantly revolving driving clutch member 65, (Figures 5 and 6) which is keyed to the timing shaft 21 by any suitable key designated by the numeral 66, so as always to revolve with the timing shaft. The driving 10 clutch member is preferably made of brass or any other non-magnetic material, and carries a suitable driving clutch disk or plate 67, and a thrust plate 68. A stationary thrust or disk plate 69 is provided juxtaposed to the movable thrust plate 68, and rigidly supported by any suitable means, such as the brackets 70. A suitable anti-friction thrust member, such as the ball bearing thrust 15 collar 71 may be interposed between the stationary thrust plate 69 and the movable thrust plate 68, thereby to minimize the friction between said movable and stationary thrust plates. The object of the two thrust plates 68 and 69 is to relieve any longitudinal 20 thrust upon the timing shaft 21.

A hollow tubular time lag shaft 72 is loosely mounted upon the timing shaft 21, and may also be suitably journaled within the stationary bearing 73, carried by any 25 suitable means such as the bracket 74. The tubular time lag shaft 72 carries a driven clutch plate 75, juxtaposed to the driving clutch plate or disc 67, and adapted to coat therewith so as to impart a rotary motion 30 to the tubular time lag shaft 72, when it is pressed against the driving clutch plate or disc 67, with sufficient pressure. The driven clutch plate or disc 75 is made of soft wrought iron, so as to be attracted by the 35 opposed poles 63 of the time relay 61. Thus, the time lag shaft 72, will be inactive or stationary, so long as the magnetic winding 60 is not energized. Whenever the magnetic winding 60 is energized in the manner de- 40 scribed hereinbefore, the driven clutch disk 75 is drawn up against the driving clutch disk 67, thereby establishing a frictional engagement between the two, and causing the time lag shaft 72 to revolve at the speed of 45 50 the timing shaft 21.

To the outer end of the time lag shaft 72, a movable contact arm 76 is secured by means of the set screw 77, or other suitable means; said contact arm 76 carrying an electrical 55 time relay contact 78 at its free end, which is in operative alignment with a corresponding stationary electrical contact 79, which is carried by the arcuate supporting bracket 80 and is electrically insulated therefrom. 60 The arcuate supporting bracket may be rigidly and stationarily secured in any suitable manner, as for instance, by means of the spacing lugs 81, carried by the magnetic core of the time relay 61. The electrical connection to the movable contact 78, may be

made through the proper grounding of the shaft 72 or by any suitable friction contact or the like, while the stationary contact 79 may be connected through a terminal binding post 82.

The stationary contact 79 is positioned slightly to one side of the vertical axial line passing through the center of the shaft 72 and the center of the timing shaft 21, so that the contact 78 and the contact arm 76 will not 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 mately four minutes from the time the motor 2 is stopped and the current ceases to flow through said motor.

This time interval, or time "lag" between 5 the instant that the motor 2 stops and the instant that the contact is established between the contacts 78 and 79, is the "normal stoppage" period mentioned heretofore.

The movable and stationary contacts 78 10 and 79 of the time relay 61 are placed in series with the lifting solenoid 44, described hereinbefore, and also in series with an electrical signal light 85, which may be suitably colored or otherwise identified, and a source of electrical energy which may be the same source 15 58, that is, the battery described hereinbefore. The connections 86, 87, 88, 55 and 89, serve to form this series circuit between the contacts 78 and 79 and the solenoid 44 and the signal 20 light 85. The signal light 85, as well as the signal light 59 described hereinbefore, may be suitably mounted upon the panel 17 in proximity to the corresponding recording instrument, and form a part of the "recording 25 unit" 20.

As mentioned hereinbefore, the visible and permanent record, upon the time card 34, will be produced so long as the solenoid 44 is not energized, since the writing point 41 of the 30 inking device 40 is brought to bear against the surface of the time card 34 by the force of gravity on the arm 38. The moment that a contact is established, however, between the movable and stationary contacts 78 and 79 respectively, of the time relay 61, and an electrical current is passed through these contacts and through the solenoid 44 (as well as through the light 85), the plunger or core 43 within the solenoid 44 is raised, thereby deflecting the arm 38 and thus withdrawing the inking point 41 from the surface of the time card 34, and thus interrupting and discontinuing the visible time record. The time 35 record is represented in the form of a line 40 in Figure 2.

Thus, it will be seen from the foregoing, that so long as the motor 2 is in operation, the contact 45 will be open, due to the energization of the primary or under-load relay winding 52, through the primary record control circuit. In this condition, therefore, the magnetic winding 60 will not be energized, and hence the contact arm 76 of the time relay 61, will be stationary in its lower, normal, 55 inoperative position. In this condition therefore, the solenoid 44 will not be energized and hence the permanent visible time record will be continued upon the time card 34. The instant that the motor 2 is shut down, however, 60 and the current ceases to flow through said motor and hence through the shunt 14, and ceases to flow through the primary record control circuit and through the relay winding 52, the magnetic core 46 will be released

from said magnetic winding 52, and hence, 65 urged by gravity, will drop a slight distance, and thus establish a contact between the movable contact 48 and the stationary contact 53, thereby establishing an electrical circuit from the source of electrical current 58, 70 through the magnetic winding 60, as well as the signal light 59.

The signal light 59 (suitably mounted upon the instrument panel 17 in close proximity to the time card 34), will thus always 75 indicate the total stoppage of the machine. The signal light 59 may arbitrarily be colored orange or otherwise designated. The passage of a current through the magnetic winding 60 instantly effects an operative engagement between the clutch discs 67 and 75, 80 through the action of the magnetic poles 63 upon the soft iron magnetic clutch disc 75, and thereby sets into motion the contact arm 76, at the rate of movement of the timing 85 shaft 21. Accordingly, if the stoppage of the motor 2 continues for a greater period of time than the "time lag" corresponding to the particular setting of the arm 76, (in the particular illustration in Figure 7, a period of 90 four minutes) the contact 78 will be brought into operative engagement with the stationary contact 79 thereby establishing, after the lapse of such predetermined period of time, (the "normal stoppage" period) an electrical 95 circuit through the source of electrical energy 58, as well as the signal light 85, and the solenoid 44; thereby raising the magnetic core or plunger 42 and thus withdrawing the inking point 41, from the surface of the time 100 card 34. Thus, only after the lapse or "lag" of a predetermined period of time, after the stoppage of the machine, will the time record be discontinued, and it is thus that the time record is automatically continued during the 105 periods of "normal stoppage" described hereinbefore.

Immediately upon setting the machine into operation, the time record is again continued, since the circuit through contact 45 110 is broken and the magnetic clutch hence becomes inactive, and the solenoid 44 de-energized. The signal light 85, arbitrarily colored green, will thus indicate when the machine is stopped, for a period in excess of the 115 predetermined "normal stoppage" period and the time record has been discontinued.

As mentioned hereinbefore, the "time lag" or the "normal stoppage" period, may be varied between suitable limits, by varying the 120 normal position of the contact arm 76 of the time relay 61, in a manner described hereinbefore. This variation or adjustment, permits the adaptation of my novel time recording system to various types of machinery and manufacturing operations. Thus, in certain types of work, the "time lag" that is, the 125 "normal stoppage" period or the time re-

quired to change the work, may be very short, while in other types of work, this time interval may be rather long.

The magnetic winding 52, upon the housing 51, is also preferably pivotally mounted in any suitable manner, as for instance upon the instrument panel 17, about the pivot screw 93, so that it may be deflected in an arcuate direction or angularly adjusted, as indicated by the arrows 91 and 92 see Figure 2. By means of the lock nut 94, the angular position of the winding 52 and of the housing 51 thereof, the effective or relative distance between said winding 52 and the pendant pivotally mounted magnetic core 46, may be varied. Thus, assuming that the core 46 will in its normal pendant position effect a contact between the movable contact 48 and the stationary contact 53, if the magnetic winding 52 is deflected in the direction of the arrow 91, the distance between the same and the magnetic core 46, will be increased, while if it is deflected in the opposite direction of the arrow 92, the distance between the core and the winding will be decreased. By thus increasing the distance between the magnetic winding 52 and the core 46, the amount of current necessary to be passed through said winding 52, in order to raise the core 46, and thereby to break the contact 45, will also be increased. Similarly, by deflecting the magnetic winding 52 in the opposite direction of the arrow 92, the current required to be passed through the winding 52 in order to break the contact 45, will similarly be decreased.

By this means, the operation of the primary relay 45, may be adjusted to any desired amount of current passing through the motor 2, and hence to any size of motor. Thus, moreover, the contact 45 may be kept open with the slightest amount of current passing through the motor 2, as for instance, a "no-load" current, that is, the current passing through the motor when the latter is merely idling, or by deflecting the magnetic winding 52 in the direction of the arrow 91, the effective current required to maintain the relay 45 open, may be increased to an amount corresponding to the "load" current in the motor 2. It will thus be seen that by this adjustment of the contact 45, it is possible to control the permanent time record upon the time card 34, either by an "idle" or no-load operation of the motor 2, or by the operation of said motor under a normal working load. If, therefore, the relay 45 is so adjusted, by the proper deflection of the magnetic winding 52, as to establish contact between the contact members 48 and 53, whenever the current passing through the motor either ceases entirely or merely drops to a no load current; then the time record 34 will not only indicate the running time of the motor 2, and the ma-

chine 1, but will actually indicate the productive time of said motor 2, and machine 1, that is, the running time of said motor and machine, under a load. The choice between a "load" time record, or "productive" time record, and a "no-load" time record, lies entirely with the management of the particular plant or factory, and may be determined by a number of factors, such as the character of the manufacturing operation and the character of the machine to which this time keeping system is applied.

Whether the time record upon the time card 34, is produced by a "load" current through the motor 2, or by any current therethrough, whether a load or a no load current, it may also be desirable to provide a signal upon the main instrument board, activated by the current of the motor 2, so as to indicate upon the signal board, whenever a machine is running idle, that is, running under no load, or as it is commonly termed in machine shops, "cutting wind". For this purpose, I may provide an auxiliary "no-load" relay mechanism 94, similar to the primary relay mechanism 45, connected electrically parallel thereto, including a similar magnetic winding 95, mounted upon a housing 96, and also including the pivotal support 97, the brackets 98, the magnetic core 99, the movable contact 100 carried thereby, and the adjustable stationary contact 101. The magnetic winding 95, is similarly shunted across the two primary record control circuit wires 15 and 16, so as to be energized in direct proportion to the current passing through the motor 2, while the two contacts 100 and 101 are connected in series with a source of electrical energy, such as the battery 58 and a suitably colored signal light 102, also positioned on the main instrument panel 17, by means of the connections 103 and 104. By so adjusting the angular position of the winding 95, as to release from its hold the magnetic core 99, whenever the load current through the motor 2 falls below a predetermined minimum, it is possible to produce a visible signal by the light 102, whenever the motor is running under no load. By this means it is therefore possible to tell at a glance just which machines are idling and which are running at a working load, and which are stopped entirely and not "recording" time.

Thus, if an auxiliary or "no-load" relay mechanism 94 is employed, together with the auxiliary signal light 102, the signal light 59 may be adjusted to indicate total stoppage of the machine, while the signal light 102 may be adjusted to indicate the idle running of the machine. The adjustment of these two signal lights, as well as the adjustment of the magnetic clutch of the time relay mechanism 61, is entirely dependant on the character of the machine and the character of the work, and upon the difference between the no

load current and the load current of the particular machine. It will thus be apparent that if on relatively light machines, or machines doing relatively light work, the no 5 load current and the load current may be so nearly equal to each other that the two signals 59 and 102 would be actuated almost simultaneously. In that event, the auxiliary signal 102 and the auxiliary contact 94 may 10 be dispensed with.

As mentioned hereinbefore, one of the objects of my invention is not only to provide an automatic electrical time recording system for recording the actual working time of 15 machines, but also to permit of the continuation of the automatic permanent time record, with the stoppage or no load running of the machine beyond the certain predetermined time lag or normal stoppage period for 20 changing the work, in the event that the stoppage of the machine beyond this predetermined period is due to some excusable cause, such as the break-down of the machine or a shortage of stock, or a necessary absence of 25 the workman from the machine or the like. The excusable causes of a continued stoppage of the machine, may thus be catalogued under a limited number of groups or headings. For the purpose of illustration, I have merely 30 employed five such causes and have applied my novel system thereto, it being understood that this number of "excusable" causes for stoppage may be more or less dependent upon the character of the work, the 35 plant or the machine.

Referring more particularly to a machine shop under normal conditions, the most frequent causes are (1) breakdown of machine, 40 (2) necessary absence of the workman from his machine, (3) awaiting new assignment or job, (4) awaiting stock or material, or (5) awaiting new tools, or sharpening a tool. These causes are designated herein arbitrarily, by the capital letters A, B, C, D, and E 45 respectively.

According to my invention, therefore, I provide a series of auxiliary record control circuits connected in parallel with each other, and shunted across the solenoid 44 of the 50 recording unit 20 upon the main instrument panel 17. Each of these auxiliary control circuits, designated by the letters A, B, C, D, and E, comprises first, a suitable switch located in the immediate vicinity of the starter 55 9, that is, within reach of the machine operator or workman, and designated by the numerals 106, 107, 108, 109 and 110 respectively. The switches 106 to 110 inclusive, may be of any suitable type, and are preferably 60 mounted upon a suitable panel 117, upon which are also mounted a corresponding series of electrical signals suitably identified by colors, numbers, letters, or the like, as the electrical lights 111, 112, 113, 114, and 115 65 respectively. The lights 111 to 115 inclusive,

are preferably positioned directly above or in some uniform relation to the corresponding switches 106, to 110 respectively. One side of each of the auxiliary control switches 106 to 110 inclusive, is connected by means 70 of the common connection 116 to one side of the solenoid 44, while the other side of each of said switches is connected in series, by parallel circuits, with the corresponding electrical signal lights upon the workman's signal panel designated in general by the numeral 75 117. From the lights 111 to 115 inclusive, upon the workman's signal panel 117, the parallel auxiliary record control circuits are continued through the wires 118 to 122 inclusive, 80 to a signal panel 123 in the shop foreman's office, where they are connected in series with a corresponding set of signal lights 124 to 128 inclusive, respectively, which are then connected in series, through the connections 85 125 to 133 inclusive, with a third and similar set of signal lights 134 to 138 inclusive upon the main recording panel 17 in the remotely located recording room 18. The latter signal lights 134 to 138 inclusive are positioned upon the panel 17 in the immediate 90 vicinity of the signal lights 59, 85 and 102, and are designated or identified by suitable colors or other indicia similar to that employed on the workman's signal panel 117 95 and the shop superintendent's signal panel 123. Each of the auxiliary record control and signal circuits is then connected to the other side of the solenoid 44, by the connection 139.

By this means, a shunt circuit may be established around the solenoid 44, through any one of a series of several parallel auxiliary record control and signal circuits, by merely closing any one of the several switches 106 to 110 inclusive. The establishment of any one of these parallel shunt circuits around the solenoid 44, with a proper relation of the resistance of the three series signal lights in each circuit, to the resistance of the solenoid 100 44, will cut down the current through the solenoid to such an extent, that it will not become effective in drawing up the magnetic core or plunger 42. By thus cutting down the current in said solenoid 44 the permanent 105 time record will be continued upon the time card 34. Thus, if a workman must stop the machine for a period of time in excess of that required to change the work in the machine, that is, in excess of the "normal stoppage" period for which the time lag, or time 110 relay switch 61 is adjusted on the instrument panel 17, for any one of the several causes of "excusable stoppage" enumerated hereinbefore, it will be necessary for the workman 115 to close one of the several signal switches 106 to 110 inclusive, in order that his time record 120 may be continued without any loss of time.

The closing of any one of the several switches 106 to 110 inclusive, automatically 125 130

lights the corresponding signal on the workman's instrument board directly above the particular switch, and also lights a corresponding signal light in the foreman's office, 5 as well as in the main recording room, directly above the particular recording instrument. The foreman, or some one directly charged with the supervision of the machines, may then immediately investigate the cause of 10 the stoppage, by visiting the particular machine, or the workman after closing one of the switches 106 to 110 inclusive, may report to the office of the foreman in order not only to explain the cause of the stoppage, 15 but also to make the necessary preparation for repair in case of a breakdown, or for securing the necessary stock, tool or assignment. In addition to thus eliminating any 20 loss of time due to necessary or "excusable" stoppage of the machine, the plant superintendent or production manager may also tell at a glance, by a visual inspection of the signal board in the main central recording room, just how many of the machines are 25 stopped and recording, that is, stopped with an "excusable" cause. By this means, a constant and accurate check may be kept not only upon the individual machine in the plant, but a check may also be kept upon each 30 particular shop or division of the plant, and moreover, the general efficiency of the plant may be estimated at a glance.

One of the objects of my present invention, is not only to produce a visible and permanent time record automatically, in a 35 remotely located central office, but also to produce a permanent time record, from which the total time of a machine or the corresponding workman, may be obtained without any 40 mental computation, that is, from which the total time may be computed by some mechanical device, such as an accumulator, counter, tabulating machine or the like. Thus, instead of producing a linear mark 45 upon a time card 34, by ink or other means, I may produce a series of spaced apertures, recesses, or notches, in a suitable time card, tape, or circular time disc or the like, each of said apertures or notches representing a 50 predetermined interval of time, which may then be passed through a suitable counter, accumulator or the like, as for instance, the present commercial forms of tabulating machines, which will mechanically add up the 55 number of such apertures or recesses, and thereby automatically compute the total or aggregate time punched or cut into said time card or disc.

Thus, according to this feature of my 60 invention, I provide an electrical or other card punching device, suitably mounted upon the panel 17, which will take the place of the inking device 40, and which is actuated by an electrical circuit, independent of the other

electrical circuits described heretofore, but 65 controlled by the latter.

Upon reference to Figure 3, there will be seen, in a diagram, the general scheme, adapted to produce a permanent time record, upon a card, by punching holes therethrough at 70 timed intervals. Thus, a punching device 140 is provided, including a plunger 141, which is formed of wrought iron, and adapted to be actuated by a solenoid 142 surrounding the same, and guided by the axial guide 75 rod 143, and the axial punch rod 144. The rod 143 may be slidably mounted in the guide 145, while the punch 144 may be guided in the stationary support 146. The stationary 80 support 146 also carries a stationary female die member 147, having an aperture 148 therein, in operative alignment with the punch rod 144, adapted to coact therewith to punch suitable apertures through the time card 149.

The time card 149 is moved longitudinally 85 at a predetermined rate by means similar to that shown in Figure 2, and described heretofore. In order to energize the solenoid 142 and hence to cause the plunger 141 to force the punch 144 through the die 147, any suitable periodic switch may be provided, properly timed with relation to the rate of movement of the time card 149, so as to cause a hole to be punched through the card at suitable predetermined intervals. The spring 95 150 interposed between the stationary support 145 and the terminal knob 151, is adapted to withdraw the punch into an inoperative position.

Thus the solenoid 142 may be connected, by 100 means of the connection 152, to the battery 58 or any other source of electrical supply, and is grounded to the apparatus, through the connection 153. A suitable timing contact cam 154 may be provided upon the feed screw 105 24. The timing cam 154 may be of any suitable construction, as for instance that illustrated in Figure 3, in which the cam proper is formed of insulating material, provided with a suitable contact member 155, intermediate the high and low points of the cam. The contact member may also be grounded, whereby an easy connection may be made therewith. Through the electrical connection 156, the opposed side of the storage battery 58, or other source of electrical supply, is connected to a suitable contact member 157, which comprises a resilient follower member 158 and a contact member 159, which is adapted to ride on the timing cam 154 and to establish an electrical connection, through the contact 155, at each revolution of the feed screw 24. Thus, at each revolution of the feed screw 24, and the corresponding linear movement of the card 149, an electrical current is passed through the solenoid 142, of sufficient strength to cause the plunger 141 to travel forward, and to force the punch 144

through the time card 149. Since the current is passed through the solenoid for a relatively short length of time, that is, the time required for the contact roller 159 to drop

5 from the highest point to the lowest point of the cam 154, the spring 150 will instantly withdraw the punch 144 from the time card.

While in the particular illustration in Figure 3 the electrical timing cam 154 is shown 10 attached directly to the feed screw 24, it is to be understood that such showing is merely diagrammatic, and that it may be more desirable to connect the timing cam 154 to a separate rotary member, which would be permanently intergeared with the timing shaft 24. The particular illustration in Figure 3, 15 however, is merely to illustrate the principle, that is, the inter-relation of the feed screw 24 and the electrical timing of the punching 20 mechanism above described.

The electrical punching circuit, including the solenoid 142, also includes an electromagnetic circuit breaking mechanism 160, comprising the two spaced contact members 161 and 162, between which an electrical connection is normally established by a suitable contact lug or blade 163, carried at the end of a suitable plunger 164 and urged into contact by means of the helical compression 25 spring 165. Thus, in the normal position of the instrument, the electrical connection is maintained between the points 161 and 162 and thus the card punching operation is continued uninterruptedly. The plunger 164, 30 guided by any suitable means, such as stationary support 166, also carries a magnetic plunger or core 167, which corresponds to the plunger 42, shown in Figure 2, which is surrounded by the solenoid 44, similar to the one 35 described heretofore. Thus, in this embodiment of my invention, the time relay circuit including the contacts 78 and 79 of the time relay 61, will actuate not the lifting plunger 42, to raise or withdraw the inking device 40, but in this modification, they will actuate the plunger 167, with the effect that the contact or blade 163, will be withdrawn, thereby 45 breaking the electrical circuit between the contact point 161 and 162, and thus interrupting the punching operation described heretofore.

Summary.

My invention may be summarized from the foregoing description and the accompanying drawings, as an electrical system for checking, indicating, or recording the production time or working operations of a machine which is electrically driven or which consumes electrical energy, such as a machine tool, textile machinery, rolling mills or electrical apparatus such as welding machines, spot welders or the like. Thus, my electrical timing system is applicable to any manufacturing operation or machine, and is arranged

to function by the variation of the current in the electrical power circuit supplying the particular machine, electrical apparatus, or the like.

The principal components of my novel electrical system are, first, the primary control circuit (14, 15 and 16 in Figures 2 and 3) which is preferably shunted into the electrical power circuit or one of the wires thereof, so as always to bear a current proportional 70 to the current in the power circuit, and a relay switch actuated by the current passing through the primary record control circuit. The relay switch, indicated generally by the numeral 45, in Figures 2 and 3, controls an 75 electrical circuit including a source of electrical energy, and connected with the actuating magnetic winding of a time relay switch, indicated generally by the numeral 61. The time relay switch in turn controls a source of 80 electrical energy passing through the recording mechanism, whereby the time record is either started or stopped, as may be desirable.

Thus in the particular illustration or embodiment of my invention, disclosed in Figures 2 and 3, the time recording devices are rendered inoperative by the current controlled by the time relay switch 61.

A series of auxiliary control or shunt circuits, are then superimposed upon one of the electrical circuits intermediate the power circuit and the final record control circuit, whereby the record may be continued uninterruptedly by the manual operation of one 100 of the several auxiliary record control circuits, said auxiliary control circuit also including a signal for indicating the operation of said auxiliary control.

While in the foregoing description, reference is made only to a "working" time record, 105 it is within the scope of my invention to record also "idle" time, as well as working time, or idle time may be recorded as an alternative to working time. The two methods 110 are complementary to each other.

My invention moreover contemplates not only the recording of working operations or "time" at a remote point, but also for indicating the same visually or otherwise, or as is 115 shown in the drawings, for both recording and indicating the same. Thus by the combination of the electrical recording and indicating circuits, the exact condition of every machine in the shop or plant may be ascertained by mere inspection of the instrument board, while a permanent time record is automatically produced by the recording instrument.

While in Figures 2 and 3, two separate or 125 independent relay switches 45 and 94, respectively, are shown, it is to be understood that the use of two such relay switches is optional, since only one is required to control the time relay switch 61. The relay switch 94 is em-

ployed only when it is desired to indicate the idle running of the machine, as shown in Figures 2 and 3. Moreover, if it is desirable, the time record may be produced not only upon the running time of a machine, but may be produced on the load running time of a machine, that is, may be produced so as to exclude therefrom an "idle running" of the machine. This may be done by mere adjustment of the relay switch 45, that is by advancing the relay, so that it will operate upon even on a "no-load" current.

My novel electrical time system overcomes a deficiency of other automatic electrical time or production checking systems attempted heretofore. Thus, the prior electrical production indicators possessed the inherent defect in producing the visual indication as soon as the machine has stopped running, that is, did not allow for a "normal stoppage" of the machine, thereby only causing confusion by a constant operation of the indicator, that is, every time a machine stopped. This has been eliminated by novel system, since only periods of absolute idleness are indicated visually or recorded upon the time record.

Having thus described my invention, what I claim as new and desire to secure by Letters Patent is:—

- 30 1. An electrical time system including an electrical power circuit, a primary control electrical circuit electrically connected with said power circuit in such a manner that the current relation of said two circuits is fixed, a time relay switch, and electrical means intermediate said primary control circuit and said time relay for actuating said time relay switch with the diminution of the current in said power circuit.
- 40 2. An electrical time system, including an electrical power circuit, a primary control circuit electrically connected with said power circuit in such manner as to bear a constant current relation thereto, an under-load relay switch adapted to be energized by said primary control circuit, a time relay switch, an electrical circuit, including a source of electrical energy, and said under-load relay switch adapted to energize said time relay switch, a recording means, and an electrical circuit including said time relay switch and

a source of electrical energy adapted to render said recording mechanism inactive when said circuit is energized by the closing of the time relay switch.

55 3. An electrical time system, comprising an electrical power circuit, a normally open and inactive electromagnetic time relay switch, electrical means intermediate said power circuit and said time relay switch for operating the latter with a diminution of current in the former, time recording mechanism and electrical means connected with and operated by said time relay switch and connected with a source of electrical energy for rendering said time recording mechanism inactive with the operation of said time relay switch.

60 4. An electrical time system, comprising an electrical power circuit, a primary control circuit electrically connected with said power circuit in such a manner as to bear a constant current ratio thereto, said primary control circuit including an under-load relay switch, adapted to be opened by a diminution of current in said power circuit, a normally active time recording mechanism, electrical means intermediate said time recording mechanism and said under-load relay switch to render said time recording mechanism inactive by the operation of said relay switch, thereby to 65 discontinue a time record with a diminution of the current in the power circuit, and a manually operable auxiliary electrical record control circuit, superimposed upon said electrical means, to maintain said recording mechanism operative, if so desired, with a diminution of the current in the power circuit.

70 5. An electric time record system, comprising a power circuit, a control circuit in shunt thereon, a relay switch in said control circuit adapted to close when the current in said control circuit falls below a certain minimum, a time switch adapted to be set in motion by the closing of said relay switch, a recording mechanism, and magnetic means to stop the operation of said mechanism, the circuit of said means being energized by the closing of said time switch.

75 90 In witness whereof I have hereunto set my hand this 22nd day of November, 1926.

100 FRANK EDWARD GOECKLER.
